UNITED STATES PATENT OFFICE.

STEPHANE PHILIPPIDES, OF NEW YORK, N. Y.

COMBINED BOTTLE CAP AND REMOVER.

Application filed May 9, 1923. Serial No. 637,899.

To all whom it may concern:

Be it known that I, STEPHANE PHILIPPIDES, a citizen of Greece, and a resident of the city of New York, borough of Manhattan, in the county and State of New York, have invented a new and Improved Combined Bottle Cap and Remover, of which the following is a full, clear, and exact description.

10 This invention relates to bottle caps and devices for removing the same and has for an object to provide an improved simplified construction which may be quickly and easily operated to remove a cap from a 15 bottle at any time.

Another object of the invention is to provide a ring for bottles having crown caps, the ring being arranged to act as a removing device when actuated in a given manner.

20 In the accompanying drawing—

Figure 1 is a side view of a bottle with certain parts broken away, the embodiment of the invention being shown in connection with the bottle.

25 Figure 2 is a top plan view of the structure shown in Figure 1.

Figure 3 is a fragmentary sectional view through the upper part of the bottle shown in Figure 1 but with a modified form of 30 ring shown in connection therewith.

Figure 4 is a perspective view of a support co-acting with the removing ring shown in Figures 1 and 3 and disclosing certain features of the invention.

35 Referring to the accompanying drawing by numerals, 1 indicates a bottle of any kind adapted to receive any desired liquid, said bottle having a neck 2 which may have reinforcing beads thereon or may be arranged

40 smooth as shown in the drawing. The neck 2, however, is provided with an annular bead 3 for receiving the crown cap 4 in the usual manner. Heretofore, lever devices of different kinds have been provided for removing crown caps but these devices were 45 separate from the cap or bottle and often times were not convenient.

In order to always provide a removing device, a ring 5 acting as a remover is mounted on the neck 2, said ring being formed of any desired material, as for instance, metal, glass or other material which may be grasped by the hand and pulled for remov-

ing the cap or may be caused to engage a support of a desired kind, as for instance, 55 the supporting bracket or shelf 6 shown in Figure 4. It will be noted that the ring 5 is loosely mounted on the neck 2 and is provided with a bore 7 of a size to pass over the bead 3 when appreciable pressure is applied thereto whereby it normally will remain on the neck 2 but may be pulled therefrom.

When the bottles are arranged as shown in Figure 4, the remover ring 5 acts as a 65 flange for supporting the bottles on the shelf 6. When it is desired to use the contents of any of the bottles on the shelf 6, the desired bottle is grasped and pulled downwardly whereupon the bottle will leave the 70 ring and cap and, consequently, the cap 4 will naturally be removed. When this is done, the bead 3 is forced through the bore 7. The ring 5 may be forced back onto the neck 2 with little effort and will remain 75 there unless positively removed. Under some circumstances, however, the bore 7 may be smaller as shown in the ring 5' where the bore 7' is of a diameter which will allow the ring to move upwardly to almost a central 80 line on the bead 3 but will not allow the ring to move thereover. This movement is sufficient to force the cap 4 off of the bead 3 but will not force the ring 5' from the neck 2.

85 It will be noted that the remover 5 is always present and, consequently, the cap 4 may be readily removed at any time by a pull or by striking the ring 5 against an object in a proper direction for causing the same to press against the cap 4.

What I claim is:—

The combination with a bottle provided with a neck having an outwardly extending bead at the upper end and provided with a 90 crown cap, of a cap removing ring loosely mounted on the neck of the bottle and provided with a bore appreciably larger than the neck of the bottle but slightly smaller than the diameter of the bead whereby the 95 bottle may be safely suspended when not in use and the cap may be quickly removed by a sufficient pressure against the ring to dislodge the cap without disengaging the ring from the neck of the bottle.

STEPHANE PHILIPPIDES.
